DESIGN FOR A BOTTLE SHIPPING CASE

Herman L. Kraeft, Cleveland, Ohio, assignor to
The Murray-Ohio Manufacturing Company,
Cleveland, Ohio, a corporation of Ohio

Application May 24, 1933. Serial No. 48,205

Term of patent 7 years

To whom it may concern:

Be it known that I, HERMAN L. KRAEFT, a citizen of the United States, residing at Cleveland, in the county of Cuyahoga and State of Ohio, have invented a new, original, and ornamental Design for a Bottle Shipping Case, of which the following is a specification, reference being had to the accompanying drawing, forming part thereof.

The drawing is a perspective view of my bottle shipping case.

The dominant feature of the design is the provision of diagonally ribbed corners of the container.

I claim:

The ornamental design for a bottle shipping case, substantially as shown and described.

HERMAN L. KRAEFT.
